UNITED STATES PATENT OFFICE.

JOSEPH F. WENTERWEST, OF LEBANON, WISCONSIN, ASSIGNOR OF ONE-HALF TO JOHN M. McDERRMOTT, OF NEW BUTLER, WISCONSIN.

RAIL ANCHOR.

1,406,594.

Specification of Letters Patent. Patented Feb. 14, 1922.

Application filed April 26, 1921. Serial No. 464,492.

To all whom it may concern:

Be it known that I, JOSEPH F. WENTERWEST, a citizen of the United States, and resident of Lebanon, in the county of Dodge and State of Wisconsin, have invented certain new and useful Improvements in Rail Anchors; and I do hereby declare that the following is a full, clear, and exact description thereof.

10 My invention has for its object to provide a simple, economical and effective rail anchor, the arrangement and construction being such that the device can be readily adjusted to the base web of a rail and firmly 15 locked thereto, by a wedged face channeled key, whereby the anchor is caused to exert a firm biting pressure upon the rail both in a horizontal and vertical direction, the wedging connection being such that tendency of 20 the rail to creep will cause a greater biting strain upon the anchor and rail parts.

With the above and other objects in view, the invention consists in certain peculiarities of construction and combination of 25 parts, as are hereinafter set forth with reference to the accompanying illustrations and subsequently claimed.

In the drawings:

30 Figure 1 represents a side elevation of a fragment of a rail and cross tie, equipped with an anti-creeping device or anchor embodying the features of my invention.

Figure 2 is a bottom plan view of the bracket portion of the anchor.

35 Figure 3 is a cross section of the rail showing the anchor mechanism in place, the section being indicated by line 3—3 of Figure 1.

Figure 4 a detail plan sectional view of the anchor, the section being indicated by line 40 4—4 of Figure 3.

Figure 5 is a longitudinal sectional view of the anchor, the section being indicated by line 5—5 of Figures 3 and 4, and

45 Figure 6 is a detail perspective view of a channel wedge key, used in connection with a bracket element of my rail anchor.

Referring by characters to the drawings, A represents a standard rail and B a supporting tie therefor. As best shown in Figures 50 1 and 3, of the drawings, the base web *a* of the rail has fitted thereto a bracket comprising a base plate 1 adapted to engage the lower face of the rail web *a*, the base plate having a depending anchor foot 2 which is 55 arranged to engage the edge of the tie B, it being understood that the creeping tendency

of the rail is indicated by the arrow X in Figure 1 of the drawings.

The longitudinal edges of the bracket base plate terminate with vertically disposed 60 neck portions 3 and 3', which are merged into horizontally disposed lip portions 4 and 4', the neck and lip portions forming in-turned flanges, which are adapted to encompass the outer edges of the rail base flange A, 65 the vertical lip portion 4' being of materially greater length than the lip portion of the companion flange.

As best shown in Figure 3, the inner opposite surfaces of the bracket flanges are of 70 such width, with respect to the rail web, that the bracket, as a whole, can be readily inserted about said web in its transverse position, as shown in Figures 1 and 3.

The vertical inner wall of one of the 75 bracket flanges, as best shown in Figure 4, is flaringly tapered as at 5, in the opposite direction from the direction of travel of the rail A, in its tendency to creep, and the adjacent inner face of the bracket base plate 80 is, as best shown in Figures 3 and 5, countersunk and horizontally tapered as at 6, the same being flared downwardly in the opposite direction from the tendency of the rail to creep, whereby a right angle, double 85 wedge shaped gripping throat is formed at this point, longitudinally of and throughout the width of the bracket.

The gripping throat is provided for the reception of a channeled key 7, the outer 90 horizontal and vertical walls of which are tapered to correspond with the tapered gripping throat formed by the bracket flange.

After the bracket has been inserted about the rail web *a*, the key is driven into place 95 and owing to the nested wedging engagement between its surfaces and the corresponding surfaces of the bracket, said wedge will cause the bracket to draw upon the rail web, both in a horizontal and vertical direction, whereby the anchor, as a whole, will firmly bite the rail web and firmly hold said rail against creeping tendency.

Owing to this double wedging engagement of the key, obviously vibration exerted upon the anchor and the tendency of the rail to creep will cause the parts to automatically tighten upon the gripping surface of the rail web, whereby any tendency of said rail to slip is avoided, and the joint as 110 a whole will for all practical purposes, be integral.

It is further understood that the vertical strain exerted by the wedgingly engaged parts, will ultimately be resisted by the lip portion 4' of the bracket biting flange, and this portion obviously is of sufficient dimension to resist breaking strain. The two parts constituting the rail anchor may be cast, drop forged or otherwise manufactured to meet the requirements of the trade, and it is understood that the dimensions of the parts may be varied to meet special requirements in the application of the anchor to different road conditions.

I claim:

A rail anchor comprising a bracket, including a base-plate having a depending anchor foot, adapted to abut and engage the lower face of a rail base flange and tie respectively, inturned gripping flanges extending from the longitudinal edges of the base-plate forming gripping throats for encompassing the edges of the rail base flange,

one of the gripping throats being formed with horizontally and vertically tapered walls, and a channeled locking key having 25 correspondingly tapered walls for snug wedging engagement with the flange throat, all the surfaces of said key being smooth, said key comprising a flat and relatively broad slightly inclined portion, a flat narrow tapered vertical portion extending downwardly therefrom at a well defined angle and a flat tapered horizontal flange extending inwardly therefrom at right angles, the key when inserted between the bracket 30 flange and rail flange being adapted to exert a bite of the aforesaid bracket upon the rail base both vertically and horizontally.

In testimony that I claim the foregoing I have hereunto set my hand at Lebanon, in 40 the county of Dodge and State of Wisconsin.

JOSEPH F. WENTERWEST.
